ERNEST B. FREEMAN, OF NEWTON, MASSACHUSETTS, ASSIGNOR TO R. F. STURTEVANT COMPANY, OF HYDE PARK, MASSACHUSETTS, A CORPORATION OF MASSACHUSETTS

HEAT EXCHANGE APPARATUS

Application filed March 24, 1932. Serial No. 600,896.

The present invention relates to heat exchange apparatus.

In the ordinary heat exchange apparatus such as an economizer employing tubular water conduits, it is found that the gases do not contact with the entire surfaces of the tubes, but permit the formation of dead spaces. These dead spaces occur in the rear of each tube (that is, on the side opposite to the side at which the gases first contact with the tube) and not only represent a diminution in the effective heating surface of the apparatus, but also form a region in which eddying takes place, thereby causing increased resistance to the passage of the gas through the apparatus. The region of eddying is a region of nearly triangular cross-section in the rear of each tube which is occupied with turbulent and slow moving currents of gas. The breaking up of the gas stream by the tubes and the eddying in the rear thereof, particularly at high gas velocities, are conducive to a high draft loss and a consequent high expenditure for draft power.

The object of the present invention is to provide a heat exchange apparatus in which eddy regions are eliminated and in which two fluids, such as water and air, may be independently heated with maximum economy and minimum expenditure for draft power.

With this object in view, the principal feature of the present invention comprises a heat exchange apparatus including a plurality of double elements, the external contour of the elements being streamlined to provide for minimum eddying. In the preferred form of the invention, each streamlined element comprises a round tube which may carry water under high pressure, provided with a streamline fairing in the rear thereof which may carry air to be preheated. Thus, the streamline fairing not only prevents the occurrence of eddies, but also affords a conduit for heating of a fluid. When the apparatus

is used as a combined economizer and air heater, the water is under the boiler pressure carried by the round portion of considerable mechanical strength, and the air which is under relatively low pressure is safely carried in the fairing.

Other features of the invention comprise certain novel features of construction, combinations and arrangement of parts herein-after described and particularly defined in the claims.

In the accompanying drawing, Fig. 1 is an elevation, partly in section, of the preferred form of the invention, and Fig. 2 is a section on line 2—2 of Fig. 1.

The illustrated embodiment of the invention comprises a combined economizer and air preheater having a casing 4 enclosing a plurality of elements indicated generally at 6. Each element 6 comprises a pair of square end flanges 8 through which extends a round water tube 10. The water tube protrudes some distance through the flanges.

Attached to the tube 10 is a hollow streamline fairing member 12. The member 12 may be of a single piece of sheet metal secured to the tube 10 by welding. The member 12, together with a portion of the outer wall of the tube 10, forms an internal passage 14 of generally triangular cross-section. The shape of the fairing member is of a shape which is aero-dynamically satisfactory for providing smooth streamline flow over the elements and preventing the occurrence of eddies. In practice, a fairing member of the type shown, of generally triangular shape, with a slightly rounded edge, is preferred because of economy of manufacture. Each end flange 8 is provided with an opening of the same shape as the external contour of the completed streamline 12. The fairing member of each element extends to a position flush with the outer surface of the flange. Both the tube 10 and the streamline element 12 are

secured to the end flanges by welding, as indicated at 16.

The elements are superposed, as shown in Fig. 1, the adjacent faces of the flanges 8 abutting to form continuous walls constituting a gas flue 18. Preferably, the contacting faces or edges of the flanges are recessed or grooved to receive the packing 20. The tubes are preferably staggered, as shown in Fig. 2. In the construction shown in the drawing, the gas passes upwardly through the apparatus; therefore, the streamline fairing members 12 are attached to the upper sides of their respective tubes. The invention may be embodied in a construction in which the gas flows in any desired direction, but in any case, the fairing is attached to the rear side of each tube, that is, to the side at which the gas last contacts with the tube.

20 The spaces 22 and 24 between the walls of the casing 4 and the flue 18 constitute inlet and outlet air chambers for conducting air to and from the air conduits 12. The air passes from the inlet chamber 22 through all of the air conduits 12 in parallel and thence to the outlet chamber 24.

The water tubes 10 may be connected in any desired manner, as by headers or return bends. In the form of the invention shown in the drawing, the water is conducted serially through the tubes and return bends 28, to be finally discharged at the outlet connection 30.

35 The present invention provides a compact, efficient, and rugged structure. It accommodates in a given space as much heating surface for water tubes as could be accommodated with the conventional round tubes, and in addition, without increasing the same space 40 occupied, affords considerable heating surface for the air by virtue of the use of the streamline fairing. The efficiency of the apparatus is greatly improved because of the elimination of wasteful eddying which would 45 oppose a high resistance to the passage of gas through the apparatus. The water tubes being of standard tube construction with circular cross-section, offer a maximum strength 50 against the water pressures. At the same time, the construction of the hollow fairing members provides ample strength for the relatively low pressure of air to be heated.

55 While I have shown the present invention as embodied in a particular construction, it is to be understood that it is not limited thereto but the specific forms and arrangements of the several parts may be varied as desired and within the scope of the appended claims.

Having thus described the invention, what 60 is claimed is:

1. Heat exchange apparatus comprising water tubes, a hollow streamline fairing member attached to each tube, and means for passing air to be preheated through the fairing members.

2. Heat exchange apparatus comprising a plurality of tubes, each of external streamline shape and including a round portion for carrying water under pressure, and a hollow fairing portion to carry air.

3. Heat exchange apparatus comprising a flue, air chambers at the sides of the flue, a plurality of water tubes extending through the flue and into the air chambers, hollow streamline fairing for the water tubes extending across the flue and terminating in the air chambers to carry air to be heated.

4. Heat exchange apparatus comprising a plurality of elements, each element comprising end flanges, a water tube extending through the end flanges, hollow streamline fairing attached to the tube and the end flanges, the elements being superposed in a manner to cause the flanges to form a flue, air chambers external to the flue for passing air to the fairing members, and connections for the water tubes in the air chambers.

5. Heat exchange apparatus comprising water tubes, a hollow angular streamline fairing member welded to each tube, and means for passing air to be preheated through the fairing members.

6. Heat exchange apparatus comprising water tubes, a hollow angular streamline fairing member welded to each tube, and means for passing air to be preheated through the fairing members, end flanges having openings to receive the tubes and fairing members, the tubes protruding beyond the flanges, the tubes and fairing members being welded to the end flanges.

In testimony whereof I have signed my name to this specification.

ERNEST B. FREEMAN.
